FREDERICK LAMATSCH, OF GRANTWOOD, NEW JERSEY, ASSIGNOR TO R. HOE & CO., INC., OF NEW YORK, N. Y., A CORPORATION OF NEW YORK

WEB ROLL SUPPORT

Application filed May 16, 1929. Serial No. 363,629.

This invention relates to improvements in supports for supporting the web rolls used in supplying paper to printing machines.

It is the especial object of the present invention to provide an improved chuck mechanism for supporting the web rolls, in which means of simple form are provided for effecting both quick and fine axial adjustments of the members which engage the roll cores, so that the rolls may be loaded into the supports expeditiously.

A further object of the invention is to provide such a construction which can be readily and quickly manipulated to effect the desired adjustments.

With these and other objects not specifically referred to in view, the invention consists in certain novel parts, arrangements and combinations which will be described in connection with the accompanying drawings and the novel features pointed out in the claims hereunto appended.

In the drawings,

Figure 1 is a sectional side elevation, partly broken away, showing a preferred form of the improved web roll support on one side of the machine.

Figure 2 is a detail sectional view looking at the other side of the machine, and illustrating the quick cam adjusting groove, no fine adjustment being shown on this side.

Figure 3 is an end view, partly in section, of the construction shown in Fig. 1, looking in the direction of the arrow 3 in that figure; and

Figure 4 is a side view of Fig. 3, looking in the direction of arrow 4 in that figure.

Referring now to these drawings, the mechanism which has been selected to illustrate the invention is a roll supporting mechanism of that type in which the rolls are carried in supports including rotary arms or racks one of which is illustrated, but it will be understood that such construction is merely illustrative of the invention and that as to certain of its features the invention can be and has been designed for use with other types of supporting mechanism.

Referring to the construction illustrated, the supporting arm 1 is provided with a

sliding sleeve 2 having a hand wheel 3 by which the sleeve can be adjusted laterally or endwise to provide a quick adjustment of the sleeve and other connections hereinafter referred to. A block 4, concentric with the sleeve, is provided with a rotatable coned head 5 which enters a lifting member 6 which enters the core 7 of the web roll 8. The quick lateral adjustment of the sleeve 2 is effected by means of a quick cam groove 9 formed in the outer surface of the sleeve 2 with which cooperates a pin 10 carried on a rod 11 and spring pressed by means of a spring 12 carried in a casing 13 secured in a hub 12 of the arm 1, this pin being moved against the spring by means of a head 14. The cam groove 9 is formed at each end with a hole 15 which is deeper than the groove 9, and the pin 10 entering this hole 15 locks the sleeve against rotation. To operate the sleeve for quick adjustment, the pin is withdrawn from the hole by means of the head 14 and on turning the hand wheel 3 the sleeve 2 is moved endwise with a quick adjusting movement.

In the particular construction shown, the lifting member 6 which enters the core of the roll is separate from the block 4, and is arranged to engage with the coned head 5 through a taper bore 16 in the end of the lifting member 6, this construction being preferably adopted so that a convenient roll loading means may be provided, such as an outer recess 18 in the lifting member 6 which may be engaged by the lifting mechanism of a roll lifting device.

The block 4 partakes of the quick endwise adjusting movement of the sleeve 2 through the medium of a key 20 carried on the block 4 which slides in a key-way 21 in the sleeve, the block being non-rotatable relatively to the sleeve.

In addition to the quick adjustment effected by the lateral movement of the sleeve, there is provided mechanism by which a fine adjustment may be secured, this being effected by moving the block 4 axially relative to the sleeve 2. While this may be effected in various ways, in the particular construction illustrated, the end of the block is recessed at 24

to receive the end of a right and left hand threaded screw 25, a thrust collar 26 being secured in a recess between the right and left hand threaded portions of the screw. The outer end of this screw is threaded into the hub 27 of a hand wheel 28. The outer end of this hub is recessed to receive a thrust collar 29 secured as by screws 30 to the hand wheel 3, the hand wheel 3 being secured to the sleeve 2, as by screws 31. It will be seen that on manipulation of the hand wheel 29 the block may be given a very fine adjustment relatively to the sleeve, so as to accurately position the coned head 5 in the bore 16 of the member 6. With the construction described, therefore, the web rolls may be quickly loaded into position, and the supporting cones readily and easily adjusted.

While the invention has been shown and described in its preferred form, it will be understood that various changes can be made in the specific construction and arrangement of the parts and that the invention is not to be restricted to the exact construction shown and described.

What is claimed is:

1. In a chuck mechanism, the combination of framing, a sleeve rotatably mounted in the framing, a concentric block, means connecting the sleeve and block so that they may have a relative axial movement but are held against relative rotation, a single cam groove in the sleeve, depressions at each end of the groove, a spring pressed member cooperating with the groove and arranged to enter the depressions for locking the parts against rotation in either direction, means for rotating the sleeve to effect a quick axial adjusting movement, and rigid means for effecting a fine adjustment of the block independently of the sleeve.

2. In a chuck mechanism, the combination of framing, a sleeve rotatably mounted in the framing, a concentric block, means connecting the sleeve and block so that they may have a relative axial movement but are held against relative rotation, a single cam groove in the sleeve, depressions at each end of the groove, a spring pressed pin cooperating with the groove and arranged to enter the depressions to lock the parts against rotation in either direction, a hand-wheel concentric with the sleeve for rotating it, and a concentric hand-wheel for effecting an axial movement of the block independently of the sleeve.

In testimony whereof I have hereunto set my hand.

FREDERICK LAMATSCH.
